UNITED STATES PATENT OFFICE.

EDGAR M. CLARK, OF NEW YORK, N. Y., ASSIGNOR TO STANDARD OIL COMPANY, OF NEW YORK, N. Y., A CORPORATION OF NEW JERSEY.

ART OF PRESSURE DISTILLATION.

1,405,286.

Specification of Letters Patent. Patented Jan. 31, 1922.

Application filed March 31, 1919. Serial No. 286,263.

To all whom it may concern:

Be it known that I, EDGAR M. CLARK, a citizen of the United States, residing at New York, in the county of New York and State 5 of New York, have invented a new and useful Improvement in the Art of Pressure Distillation, of which the following is a specification.

My present invention relates to the art of 10 pressure distillation of heavy petroleum oils as conducted for the purpose of converting such oils by pyrogenesis into lighter oils of the character of gasoline. The invention will be fully understood from the following 15 specification taken in connection with the accompanying drawing, which represents a side elevation, partly in section, of a pressure-cracking still of the tubular type and built in accordance with the principles of 20 this invention.

Referring more particularly to the drawing, the numeral 1 designates the drum of the still, this drum, as shown, being of horizontal cylindrical form and supported above 25 a still-furnace 2 by columns 3. Within the furnace there is mounted an inclined tube bank 4, the tubes of which are fitted into end-headers 5, the latter being connected by vertical legs 6 with the drum 1.

Above the still-drum there is mounted a 30 vapor drum 7, also preferably of horizontal cylindrical form as illustrated, and supported and connected with the still at one end by a vapor pipe 8, the opposite end being supported by a roller 9 resting upon the 35 top of the still-drum. By this method of mounting the vapor drum, the strains due to the expansion and contraction of the parts are reduced to a minimum. Near one 40 end of the vapor drum 7, the latter is provided with a transverse tube sheet 10 in which there are secured two horizontal rows 45 of tubes, the upper row being designated 11 and the lower row 12. All of the tubes are provided with small perforations for the escape of vapors as will later appear, the upper row 11 being capped at the outer end as shown at 13, while the lower row 12 has downturned elbows and nipples, as shown at 50

14. Spaced away from the tube sheet 10 there is a false head 15 which terminates short of the upper side of the vapor drum to leave a free vapor passage 16 over its upper edge. An overflow pipe 17 passes 55 through the false-head 15 and is fastened

to the tube sheet 10 some distance below the top of the drum. The horizontal leg of this overflow pipe is connected by an elbow with a vertical leg 17' which extends downward centrally through the vapor connection 8 60 and terminates near the bottom of the still-drum 1 and preferably just above the opening of the rear or longer leg 6. A dam 6' extends transversely of the bottom of the drum in front of the leg 6. A direct passage 65 through the tube sheet 10 is afforded by a check valve 18 which opens for flow from left to right as seen on the drawing. A feed pipe 19 is tapped into the other or left-hand end of the drum as seen on the drawing and a draw-off pipe 20 into the bottom of the drum near the tube sheet 10. The draw-off pipe or tar-line of the still is designated 21 and is preferably tapped into the lowest point of the still which is the bottom 70 of the lower tube header 5.

Both the still drum and the vapor drum are provided with manheads at the ends and top and with gauge glasses as shown. There will also be the customary equipment of 80 pressure gauges and pyrometers or high-temperature thermometers for taking the temperatures and pressures within the vapor drum and still drum.

A vapor pipe 22 is tapped into the top of 85 the vapor drum and leads to a condenser (not illustrated). Preferably, the still illustrated by the present drawing will form one of a battery, all of the stills in the battery having their individual water-cooled condensers connected with the vapor-lines 22 and through the latter with the receiving-house equipment illustrated in my prior Patent No. 1,132,163, it being understood 90 that the still represented by the present 95 drawing is to be substituted for the type of still illustrated and described in the said patent.

In the conduct of the distilling operation employing the apparatus above described, the procedure may be as follows:

It will be assumed that the still has a charging capacity of 13,000 gallons and that the vapor drum between the tube sheet 10 and the far end and up to the level of 105 105 the overflow-pipe 17 has a capacity of 6,000 gallons. At the beginning of the operation, the still and drum will be charged with the named amounts of gas oil from mid-continent crude petroleum, for example, a 32° B. 110

oil. The still will now be fired and raised to a temperature of, for example, 400° F. while under atmospheric pressure. During this initial heating, any traces of water and 5 of light oils which may be present in the gas oil will distill over freely through the water-cooled condenser (not shown) and be evacuated from the system. When a temperature of about 400° F. has been attained, 10 the receiver of the still will be connected through the means shown in my prior patent referred to with the high-pressure gas line, and by this means the free spaces in the condenser, still and drum will be 15 charged with petroleum oil gas up to the operating pressure, for example, 95 pounds per square inch. It will be noted that this gas enters the vapor drum through the vapor line 22, and by reason of the check 20 valve 18 is permitted to pass directly from the vapor drum into the still 1. The operating pressure having thus been established in the apparatus, firing of the still will be continued until the temperature of the 25 oil body in the still reaches about 725 to 728° F. At this temperature, decomposition of the gas oil in the still 1 will proceed rapidly, the gasoline vapor thus generated will pass out through the vapor connections 8 over the top of the false-head 30 15 and by displacing the oil between the tube-sheet and false-head will enter the rows of tubes 11 and 12 and escape from the latter, bubbling through the deep liquid body 35 in the vapor drum. In the earlier stages of the operation, there will be almost complete condensation of the vapors in their passage through this liquid body, such condensation adding to the volume of the liquid in the 40 drum and causing it to overflow back into the still. Within a short time the transfer of heat from the still to the vapor drum in this fashion, raises the temperature of the oil in the vapor drum to about 510° F. at 45 which point the gasoline vapors will pass unchanged through the oil body, only those distilled fractions from the oil in the still which are substantially heavier than gasoline being condensed by bubbling through 50 the oil in the vapor drum. The gasoline vapors will pass continuously out through the vapor-line 22 to be condensed in the water-cooled condenser (not shown), and evacuated from the receiving drums in the 55 receiving house, as described in my prior patent referred to, the pressure being mean- time constantly maintained at the predetermined figure by the open connection between the still and the 95-pound gas-line. 60 The normal initial running condition of the apparatus therefore will be substantially as follows:

Temperature of the oil in the still, 725° F.
Temperature of the oil in the vapor drum, 65 510° F.

Vapors of gasoline mixed with a very considerable proportion, amounting perhaps to ten times their mass, of heavier oil vapors, arise continuously from the still and by the 70 passages described are caused to issue from the orifices in the submerged pipes 11 and 12. In their passage through the oil body, the vapors undergo fractional condensation, that portion of the vapors which it is not desired to collect as distillate being condensed and overflowing back to the still 75 through the pipe 17.

When these normal running conditions have been established, the still will be fired as such a rate as to produce approximately 320 gallons of distillate per hour, which distillate may have a gravity of 57° B. and a maximum boiling-point of 500° F. The introduction of fresh stock into the vapor drum 7 through the feed pipe 19 will 80 now be begun, such fresh stock being fed at the same rate at which the distillate is produced so that the total volume of oil within the system remains constant. The stock thus in-fed may be the same as that 85 originally charged, that is, 32° B. mid-continent gas-oil, or it may be a lighter oil, for example, an oil of 36° B. of the same general character. As a variant of the process the stock fed to the vapor drum 90 may be a medium heavy crude distillate containing a considerable percentage of naphtha fractions, for example, the crude cut known as light paraffin gas-oil and containing up to 20% naphtha fractions produced by cracking at atmospheric pressure 95 in the later stages of the run in the fractional distillation of crude petroleum. If such light paraffin gas-oil be employed as a feed stock, the naphtha fractions thereof 100 will be immediately vaporized upon the entrance of the oil into the vapor drum, the drum serving as a skimming still for this purpose. It will be understood that if this 105 variation of procedure is resorted to, the naphtha fraction of the infed stock must be accounted for in governing the feed rate and distillation rate.

A normal run under the conditions described will be completed in 60 hours, the distillate being taken over at the rate of 320 gallons per hour during that time and feed stock being introduced at the same rate. Thus, the total gallonage of the stock charged and fed will be 38,200 and the total distillate 115 taken off 19,200 or approximately 50%. At the end of the run there will remain in the still 13,000 gallons of relatively heavy tar, for example, 18° B., while there will be in the drum 6,000 gallons of intermediate oil 120 having an approximate gravity of 38° B. This intermediate oil, being in its entirety a distillate, will be free from coke or suspended solids and suitable for use as a feed stock, or by re-distilling it a considerable percent- 125 130

age of fractions within the heavy naphtha and refined oil or kerosene range may be recovered.

I have found, under the conditions of operation described, that loss of heat from the vapor drum 7, together with the heat absorption of the cold infed stock, will generally be sufficient to maintain the desired temperature of approximately 510° F. within the drum. The temperature may be maintained at a lower figure, however, and accurately controlled by constantly withdrawing any desired amount of oil from the vapor drum by the pipe 20, passing this oil through a cooler and feeding it again to the drum at the same rate at which it is withdrawn. It is to be noted, with respect to the process described in the foregoing, that the temperature within the still, assuming a constant distillation rate and a constant gravity of distillate, remains substantially uniform throughout the run. Thus, in the example given, the temperature may be expected to remain between the limits of 725° to 728° F., with careful firing.

It is also to be noted that the continuous refluxing of the oil from the drum into the still, together with the continuous feeding of the drum, is made to benefit the operation of the still itself by returning this reflux in such a position that it passes immediately to the tube bank 2, diluting the tar or heavy oil of the still-drum as the latter enters the rear conduit 6 in its thermo-siphon circulation. As a result of such continuous dilution, several beneficial effects are obtained, i. e., the deposition of carbon within the tubes 4 is lessened, and the deposition of carbon within the drum 1 is increased, both by reason of the greater relative density of the tar in this drum and because of the slow circulation of the oil through it. The dam 6' is of further aid in preventing deposition of carbon in the tubes in that it gives a better opportunity for the settling out of suspended carbon in the drum.

A second method of operation may be as follows:

Assuming that the still has the same capacity as in the foregoing; that is, 13,000 gallons, but that the vapor drum is of small size so that it has a liquid capacity of only 3,000 gallons, the run will be started by charging the still with only 8,000 gallons, the drum being empty. The still will be fired in the usual manner until a temperature of about 400° F. has been attained, but during this time the distillate, consisting of water and very light oil, will be continuously drained out of the drum by the pipe 20. This method of operation has the advantage that the water and light oil—the so-called "drips" of the distillation process—are evacuated from the system without it being necessary to heat up the vapor drum

or any oil therein. After these drips are off, the still may be put under pressure in the manner heretofore described and firing continued until the still is brought up to running condition. During such initial 70 firing, distillate will continue to come over from the still and to accumulate in the vapor drum until the latter has been filled, the temperature of the vapor drum being, during this time, so low that substantially no 75 vapors will pass to the water-cooled condenser. When normal conditions are established, therefore, the contents of the still will have been reduced to about 5,000 gallons, and the vapor drum will contain about 80 3,000 gallons of oil which will be its capacity up to the overflow pipe. When these conditions are established, the still will be fired at such a rate as to produce 250 gallons of distillate per hour, and feed stock will be 85 introduced at the rate of 350 gallons per hour, the still temperature and drum temperature remaining as described in the previous example. Running conditions will be maintained for 74 hours during which time 90 there will be taken off 18,500 gallons of distillate while 25,900 gallons of stock will have been fed. The total of stock charged and fed will, therefore, be 33,900 and the distillate produced approximately 55% of this. 95 There will remain in the still 12,400 gallons of tar, while the drum will contain 3,000 gallons of intermediate distillate.

The method of operation last described has the advantage of giving a shorter period of 100 preliminary firing before the still comes to its normal running condition. Thus, it has been stated that the so-called "drips," that is, the water or lighter constituents of the charging stock may be withdrawn directly 105 from the drum without permitting the latter to heat up, and a shorter time is, therefore, required for getting off the drips. The relatively small proportion of the total oil treated during the cycle which is present in 110 the still at the beginning of the operation, reduces almost proportionately the time required for attaining the running condition. Nor is the saving of coal in this initial heating sacrificed in the subsequent stages of the 115 run for the excess of the stock fed to the drum over the distillate is continuously heated as it enters the system by absorbing the latent heat of vaporization of the fractionally condensed constituents of the outgoing vapors, thus utilizing heat energy which would otherwise be dissipated to the atmosphere. In addition to these beneficial effects I also consider it of advantage to introduce into the still, during the run of the latter, as 120 large a proportion as possible of fresh stock, a result which is attained in the present instance by an operation which may be described as not only feeding the still while running, but also charging it while running.

I have found that in the operation as described in the foregoing the drum 7, containing a relatively large body of liquid with which the vapors come into intimate contact, 5 acts as a stabilizer of the entire process, being of the greatest aid in maintaining uniform conditions of temperature, distillation rate and distillate gravity. By the application of the principles of my prior Patent 10 No. 1,132,163, the pressure in the still may be kept constant within the narrowest limits. This uniformity and accuracy of pressure control, when coupled with the stabilizing effect on the distillation and control of the 15 character of the distillate resulting from the use of the drum 7, gives to the entire process, when worked on the largest commercial scale, a regularity of action which it is difficult to achieve even under laboratory conditions. 20 This result, furthermore, is attained without the use of any sensitive automatic control apparatus, but solely by designing the system in such a manner that it shall be inherently stable. 25 It is to be particularly noted, with respect to the detailed construction of the vapor drum 7, that the latter affords an expansion chamber of considerable size at the end at which the vapors enter. In this chamber 30 opportunity is afforded for the dropping out of entrained liquid particles from the vapor stream. The immediate return to the still of these unvaporized particles without unnecessary cooling thereof not only conserves 35 fuel but prevents the fouling and stoppage of the vapor pipes and orifices in the condensing system proper, the best design of the latter being to a large extent incompatible with its use as a mere separator. 40 While I have in the foregoing described in some detail an apparatus constructed in accordance with my invention together with the preferred method of operating the same and some variants thereof, it will be understood 45 that this is only for the purpose of making the invention more clear and that the invention is not to be regarded as limited to the details of construction or operation described, nor is it dependent upon the soundness or accuracy of the theories which I have advanced as to the reasons for the advantageous results attained. On the other hand, the invention is to be regarded as limited only by the terms of the accompanying claims 55 in which it is my intention to claim all novelty inherent therein as broadly as is possible in view of the prior art.

What I claim is:

1. The improvement in the art of distilling heavy oil under pressure for the production therefrom of lighter oil, which consists in bringing substantially the entire body of the oil vapors produced within the still and while under their pressure of production into intimate contact with a large

relatively stationary body of oil, maintaining the said oil body at a constant temperature substantially below the temperature in the still, whereby the issuing vapors are fractionally condensed, causing oil to flow 70 continuously from the said large body into the still, and taking off and separately condensing and collecting the vapor constituents which escape condensation in the oil body. 75

2. The improvement in the art of distilling heavy oil under pressure for the production therefrom of lighter oil, which consists in causing substantially the entire body of the vapors produced within the still to 80 bubble through a large relatively stationary body of oil, maintaining the said oil body at a constant temperature substantially below the temperature in the still, whereby the vapors are fractionally condensed, and continuously feeding the still from the overflow from said oil body. 85

3. The improvement in the art of distilling heavy oil under pressure for the production therefrom of lighter oil, which consists in bringing substantially the entire body of the oil vapors produced within the still and under their pressure of production into intimate contact with a large relatively stationary body of petroleum oil, maintaining 90 the temperature of said oil body substantially below the temperature in the still, whereby the vapors are fractionally condensed, continuously introducing fresh oil into the said oil body, continuously feeding 95 the still from the overflow from the said oil body, and taking off and separately condensing and collecting the vapor constituents which escape condensation in the said oil body. 100

4. The improvement in the art of distilling heavy oil under pressure for the production therefrom of lighter oil, which consists in beginning the pressure distilling operation with an oil body in the still of a 110 volume considerably less than the full charge thereof, and introducing fresh oil into the still at a rate greater than the production of distillate therein, so that the mass of oil under treatment increases during the process to a volume not greater than the full charge. 115

5. The improvement in the art of distilling heavy oil under pressure for the production therefrom of lighter oil, which consists in beginning the distilling operation with an oil body in the still of a volume considerably less than the capacity thereof, forming and maintaining a body of liquid derived from the condensation of heavier 125 vapors given off during distillation of said body of oil, passing vapors of the distillation of the body of oil to said body of liquid, thereby condensing heavier portions thereof, introducing fresh oil into said body of liquid 130

at a rate greater than the rate of formation of distillates from the vapors passing through the body of liquid and returning to the body of oil in the still the liquid 5 added to said body of liquid as fresh oil and condensate.

6. The improvement in the art of distilling heavy petroleum oils under pressure for the production therefrom of lighter oil, 10 which consists in passing the vapors issuing from the still into an expansion chamber, maintaining such expansion chamber at a temperature not substantially below that of the still, continuously returning to the still 15 from the expansion chamber the precipitated unvaporized oil particles subjecting the vapors passing from the expansion chamber to fractional condensation, returning the condensate to the still, and taking off and 20 separately condensing and collecting those vapors which escape condensation in the fractional condenser.

7. A petroleum distilling apparatus comprising a still, a vapor outlet therefrom, an expansion vessel in communication with 25 the vapor outlet passage and mounted above the still to drain thereto by gravity, a liquid containing chamber, means for passing vapor from said expansion vessel into said liquid chamber into the liquid therein, 30 thereby condensing a part of said vapors, and means for conveying excess liquid from said liquid chamber to the still by gravity.

8. A petroleum distilling apparatus comprising a still, a drum mounted above the 35 still, an overflow connection in said drum for maintaining a constant level therein, said overflow connection extending into the still below the normal liquid level therein, and a separate vapor connection communicating with the still above the liquid level therein and with the drum below the liquid 40 level of the latter.

EDGAR M. CLARK.
